US00D835510S

(12) **United States Design Patent** (10) **Patent No.:** **US D835,510 S**
Arora (45) **Date of Patent:** **** Dec. 11, 2018**

(54) **JAR**

(71) Applicant: **Just Funky LLC**, Richfield, OH (US)

(72) Inventor: **Rajnish Arora**, Wooster, OH (US)

(73) Assignee: **Just Funky LLC**, Richfield, OH (US)

(**) Term: **15 Years**

(21) Appl. No.: **29/624,658**

(22) Filed: **Nov. 2, 2017**

(51) LOC (11) Cl. **09-01**

(52) U.S. Cl. **USPC D9/505**

(58) **Field of Classification Search**
 USPC D9/424, 428, 435, 454, 500, 503, 504,
 D9/516, 520, 715; D7/300, 396.2,
